UNITED STATES PATENT OFFICE.

SEBASTIAN G. BRINKMAN, OF PERTH AMBOY, NEW JERSEY.

REFRIGERATOR.

Application filed February 23, 1927. Serial No. 170,363.

- This invention relates to improvements in refrigerators, and more particularly to a double or spaced wall porcelain refrigerator, and the method of making the same.
- 5 An object of the invention is to provide a refrigerator formed of a plurality of cooperating compartments, each compartment being built with spaced porcelain walls, between which is a vacuum, or if desired, dead air may be trapped therebetween.
- 10 A further object of the invention is to provide suitable means and a novel process whereby the spaced walled porcelain boxes or compartments may be molded and baked.
- 15 A still further object of the invention is to provide a process whereby the spaced walled porcelain compartments may be reinforced and further provided with means whereby the usual refrigerator fittings may be supported.
- 20 Other objects will appear as the description proceeds.
- In the accompanying drawings which form a part of my application,
- 25 Figure 1 is a perspective view of a refrigerator made in accordance with my invention;
- Figure 2 is a sectional view taken on the line 2—2 of Figure 3;
- 30 Figure 3 is a sectional view taken on the line 3—3 of Figure 2;
- Figure 4 is a front elevation of the outer plaster mold;
- Figure 5 is a sectional view taken on the line 5—5 of Figure 6, and
- 35 Figure 6 is a sectional view taken on the line 6—6 of Figure 5.
- Like characters of reference are used throughout the following specification and 40 the accompanying drawings to designate corresponding parts.
- In brief, I provide a porcelain refrigerator composed of one or more integrally formed spaced walled compartments, which 45 are sealed or closed by means of doors formed in the same manner and from the same material.
- The refrigerator compartments 20 are formed in the following manner: A working 50 table 1 is provided for supporting the mold
- and has an opening 2 cut through it near its central portion of a size corresponding to the largest outside dimension of the inner mold. The core 3 is formed with four sides and a top, and is open at its bottom. The 55 lower portion of the inner core 3 is outwardly flared as at 4, to provide for the bevel usually found in the front of refrigerator compartments, and cooperates with a correspondingly beveled surface of a door, 60 to form a tight joint. It will be seen that the core 3 is slidable within the opening 2, and is supported by the table in any suitable manner. The top of the core 3 is closed except for a central opening 5, the sides of 65 which are beveled and cooperate with the beveled sides of a central supporting head 6, carried by the adjustable standard 7. It will be understood that all parts of the core 3 and head 6 are formed of plaster.
- 70 A recessed base plate 8 of plaster is positioned about the core 3, and seats on the annular flange about the lower edge of said core. The plate 8 is supported on the table 1, and supports the mold 9 in spaced relation to the core 3. The mold 9 comprises four interlocking walls of plaster and is provided with an interlocking removable top 10. When the base plate, core and mold are in position, the several joints between the 75 same are sealed with clay to prevent leakage of the slip when poured in the mold. A filling tube or pipe 11 of brass extends into the space between the core and mold, while an overflow pipe 12 also extends through the 80 upper portion of the mold 9 to let the air out of the mold and to give warning when the mold is completely filled with the clay slip. A drain pipe 13 extends upward into the space between the core 3, and mold 9, and is 85 used to drain off the undesired portion of the clay slip, after the walls of the compartment being molded have been formed to the desired thickness. This operation is usually calculated by time, since the plaster between 90 the core and mold absorbs the moisture in the clay slip, and causes a wall to be built up against the sides thereof.
- 95 Plugs 14 extend through the core 3, towards the inner wall of the mold 9, and pro-

vide passages 15 in the refrigerator compartments 20, for the passage of air through the same, or through several compartments. The plugs 14 being made of plaster, will also cause the clay slip to form a wall about the same. Likewise the spaced walls of the compartments will be reinforced, by inserting plaster plugs 16 through the core 3, and permitting the clay slip to build up around the same. Plugs 17 will be inserted through the core 3 to form openings in the inner wall or surface of the compartments to receive supporting means for the trays 18. The compartments will be so formed that the passages 15 are in alinement with similar passages in other compartments, so that a circulation of air may be had between the several compartments of the refrigerator.

Assuming that the core and mold are in position, the method of making the compartments is as follows: The space between the core and mold is completely filled with a clay slip, through a funnel in the filling pipe, until the slip starts to run out of the overflow pipe 13, at which time the overflow pipe is closed by means of a suitable plug. Of course the funnel is kept full of the slip. The slip is permitted to set for approximately four hours, during which time, the moisture will be drawn out into the plaster walls of the core and mold, and spaced walls will be built up from the slip. The drain plug is then removed and all of the slip remaining in liquid form will be drained from the mold. At the same time an air line will be connected to the filling pipe and a low pressure of air will be directed into the space between the walls formed by the slip. In this manner the upper or outer wall formed by the slip will be supported on an air cushion, and will be kept from collapsing. After this the core is lowered through the central opening in the table, while the supporting head is held in its raised position to support the inner horizontal wall formed by the slip. After a predetermined length of time the air may be turned off and the supporting head lowered through the opening in the table, and the mold taken apart. It will thus be seen that a spaced walled compartment will be formed, having reinforced walls. The refrigerator fittings may be applied in any suitable manner. It will be understood that the doors for the compartments will be formed in the same manner, but with different molds. The compartment walls will be approximately one half inch in thickness, while the space therebetween will also be approximately one half inch. The box or compartment will usually be fired in a kiln while in a biscuit state, after which a plurality of glazing coats will be applied to the box, which will then be burned a second time in a gloss kiln, to form the completed

article. However, one firing may be used instead of two firings.

The space between the walls of the compartment may be filled with dead air, or may be a vacuum, as desired.

If several compartments are to be used together to make a refrigerator, suitable bolts 19 will be employed to hold the said compartments in place. The compartments may be supported on a suitable base 21, or may be placed directly on the floor, if desired.

From Figure 2 of the drawings, it will be apparent that the compartment on the upper right hand corner will be the ice compartment, and that the cold air will pass down through the passage into the lower right hand compartment, and from there to the lower left hand compartment, and up into the upper left hand compartment, and finally back into the upper right hand compartment. Hence a complete circulation of the air in the several compartments will be had, thereby keeping the temperature in the compartments at a fairly even degree. It will be apparent that no insulating material will be used as in the ordinary form of refrigerators, and the vacuum or dead air between the spaced walls will serve to retain the cold within the compartments. Of course, the compartments could be used just as successfully as a medium for heating, as the double spaced wall construction renders the compartments thoroughly air tight and insulated.

Many minor changes in detail of construction may be resorted to without departure from the spirit of the invention.

Having thus described my invention what I claim as new and desire to secure by Letters Patent of the United States is:

1. A refrigerator including a plurality of molded spaced double walled porcelain refrigerator units, each having spaces for a vacuum between its walls, and integrally formed reinforcing areas built up between the several walls of each unit.

2. A refrigerator including a plurality of separate molded spaced double walled porcelain refrigerator units, each having spaces for a vacuum between its walls, and registering air passages formed through the adjacent walls of said units.

3. A refrigerator including a plurality of separate molded spaced double walled porcelain refrigerator units, each having spaces for a vacuum between its walls, registering air passages formed through the adjacent walls of said units, and molded areas formed in the side walls of said units adapted to receive tray supporting elements.

4. A refrigerator including a plurality of separate porcelain refrigerator units, each of which is provided with spaces for a vacuum between its walls, the adjacent walls of ad-

jacent units having aligned registering air passages to permit the circulation of cold air through said units, and internal means for holding said units together.

5. A refrigerator including a plurality of separate porcelain refrigerator units, each of which is provided with spaces for a vacuum

between its walls, said units having registering and interlocking air passages between the same, and means for holding said units together.

In testimony whereof I affix my signature.

SEBASTIAN G. BRINKMAN.
